UNITED STATES PATENT OFFICE.

CHARLES NELSON, OF NEW YORK, N. Y., ASSIGNOR TO S. STERNAU & COMPANY, OF BROOKLYN, NEW YORK, A COPARTNERSHIP.

DESIGN FOR A TOWEL-RACK.

41,956.

Specification for Design.

Patented Dec. 5, 1911.

Application filed February 11, 1911. Serial No. 608,125. Term of patent 7 years.

To all whom it may concern:

Be it known that I, CHARLES NELSON, a citizen of the United States, and a resident of the borough of Brooklyn, county of Kings, city and State of New York, have invented a new, original, and ornamental Design for Towel-Racks, of which the following is a specification, reference being had to the accompanying drawings, forming a part hereof, in which—

Figure 1 is a plan view. Fig. 2 is a front elevation; and Fig. 3 is an end elevation of the design.

I claim:

The ornamental design for towel rack, as shown.

CHARLES NELSON.
